(57) **CLAIM**

The ornamental design for an automobile lower grille, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of an automobile lower grille showing our new design;

FIG. 2 is a front view thereof;

FIG. 3 is a rear view thereof;

FIG. 4 is a side view thereof;

FIG. 5 is top view thereof; and,

FIG. 6 is a bottom view thereof.

It will be understood that the broken lines shown in the drawings illustrate portions of the automobile lower grille that form no part of the claimed design.
